ATTORNEY

UNITED STATES PATENT OFFICE.

SHIRLEY S. WEEKS, OF PROVIDENCE, RHODE ISLAND, ASSIGNOR TO ASSOCIATED ENGINEERING & SUPPLY COMPANY, OF SAN FRANCISCO, CALIFORNIA, A CORPORATION OF CALIFORNIA.

LIQUID-FUEL-BURNING APPARATUS.

Application filed July 22, 1920. Serial No. 398,226.

To all whom it may concern:

Be it known that I, SHIRLEY S. WEEKS, a citizen of the United States, residing at Providence, in the county of Providence and State of Rhode Island, have invented new and useful Improvements in Liquid-Fuel-Burning Apparatus, of which the following is a specification.

This invention relates to fuel oil burning apparatus, and more particularly to automatic controlling mechanism for regulating the intensity of the fire.

In Patents No. 1,197,053 of H. L. Nicholson and S. S. Weeks, dated September 5, 1916 and No. 1,314,174 of S. S. Weeks and C. D. Stewart, dated August 26, 1919, are disclosed oil burning apparatus of the above character in which the fuel oil is atomized by steam and the supply of steam and oil to the burners is varied by steps.

The principal object of the present invention is to provide an oil burning apparatus of the above character in which the oil is atomized mechanically through the use of high oil pressure in connection with burner nozzles designed to atomize the oil under the influence of pressure.

According to the present invention the intensity of the fire is changed or regulated by varying the pressure at which the oil is supplied to the burners through the operation of one or more pressure regulating valve devices.

In the accompanying drawings; Fig. 1 is a diagrammatic view of a battery of two steam boilers and my improved oil burning apparatus applied thereto; Fig. 2 a sectional view of one of the master controller units; Fig. 3 a sectional view of a set of damper regulating units; Fig. 4 a sectional view of one of the pressure regulators; and Fig. 5 a sectional view of one of the pressure reducing valves.

A battery of two steam boilers 1 and 1^a is shown in Fig. 1 and the furnace of each boiler is equipped with a plurality of oil burners B designed to mechanically atomize the fuel oil under high pressure, it being understood that any number of boilers may be provided and that several oil burners are usually provided for each furnace, although only two are shown in the drawings, for the sake of simplicity.

A common fuel oil supply pipe 2 for all the oil burners receives oil under pressure 55 from a single pump 3 which may be operated by steam supplied through pipe 4.

The automatic regulation of the apparatus for the battery of boilers is governed by a single master controller comprising 60 units M¹ and M² and the draft dampers 5 for each boiler are controlled by a damper regulator comprising units D¹ and D².

For reducing the pressure of oil supplied to the burners of each boiler, reducing valves 65 R¹ and R² and regulating valves V¹ and V² are provided.

The units M¹ and M² of the master controller are identical in construction and each comprises a casing 6 containing a diaphragm 7, subject on one side to the pressure of steam generated in the system as supplied through pipe 8 and on the opposite side to the pressure of an adjustable spring 9.

The diaphragm 7 is adapted to operate a valve 10 for varying the pressure on one side of a differential piston having differential piston heads 11 and 12, the smaller piston head 12 being constantly subject to 80 the pressure of fuel oil as supplied by the pump to the supply pipe 2 and thence through a branched connecting pipe 13.

A return or exhaust pipe 14 is connected to the space intermediate the piston heads 11 and 12 and when the valve 10 is opened, communication is established from the chamber adjacent to the piston head 11 through a passage 15 to said pipe 14. A pipe 16 connects the master controller unit M¹ with 90 the damper controller unit D¹ of each boiler and a pipe 17 connects the unit M² with the unit D².

The damper controller units D¹ and D² are identical in construction and each comprises a casing 18 containing a piston 19 with the chamber below the piston connected to the return pipe 14 and having a piston stem 20 connected to a chain 21 which passes over a sheave 22.

The sheave 22 is connected to a rod 23 for operating the damper 5 and to a rod 24 for operating a shaft 25, through which the ash pit doors 26 are operated.

Associated with the controlling apparatus of each boiler are regulating units V¹

and V^2 and reducing valves R^1 and R^2 .

The regulating units V^1 and V^2 are identical in construction and each comprises a casing 27 containing a valve 28 operatively connected to a piston 29, subject on one side to the pressure of a coil spring 30.

The reducing valves R^1 and R^2 each comprise a casing 31 containing a diaphragm 32, subject on one side to the pressure of an 10 adjustable spring 33 and carrying a yoke 34 for operating a valve 35.

When the apparatus is to operate automatically, a globe valve 36, through which fuel oil may be supplied directly from the 15 supply pipe 2 to the burners B, is closed at each boiler, while globe valves 37 and 38 are opened.

In operation, assuming the pump 3 as 20 supplying oil under a pressure of 225 pounds, for example, and that the reducing valve R^1 is set for 175 pounds and the reducing valve R^2 for 200 pounds, if the steam pressure is low, the springs 9 of both master controller units M^1 and M^2 will hold the 25 diaphragm 7 in its upper position against the low steam pressure so that the valve 10 in each unit will be held closed.

Fuel oil under pressure supplied from the pump 3 through pipe 13 to the piston 30 head 12 will then equalize through restricted port 39 into the chamber above the piston head 11, so that the differential piston of each master controller unit will be held in its lower position as shown in Fig. 2.

35 The pipes 16 and 17 are thus connected to the return pipe 14 and consequently the opposite sides of the piston 19 of each damper regulator unit D^1 and D^2 is subject to the same pressure of the return pipe 40 14. The shaft 25 and the stack damper 5 are provided with the respective weighted arms 40 and 41, so arranged that they tend to move the dampers to their full open positions and also the sheave 22 with the connected pistons 19 to their upper positions, 45 as shown in Fig. 3.

50 Pipe 42 leading from the chamber above piston 19 of the damper regulator unit D^1 is connected to the top of the pressure regulator valve V^1 and pipe 43, leading from the chamber above piston 19 of the unit D^2 is connected to the top of the regulator valve V^2 , so that the piston 29 of both valves is subject to the pressure of the return pipe 14.

55 The pressure of fuel oil supplied to the pipe 2 therefore acts on the piston 29 of each regulator valve to open each valve 28, and fuel oil will then flow at the full pump pressure of 225 pounds, through the open 60 valve V^1 and pipes 44 and 45 to the burners B.

When the steam pressure in the boilers reaches a predetermined degree, the diaphragm 7 of the master controller unit M^1 65 is operated by the increase in pressure to

open valve 10 and thereby vent fuel oil under pressure from piston head 11 through passage 15 to the return pipe 14.

The fuel oil pressure acting on the piston head 12 then shifts the differential piston, 70 so that communication is opened from the pipe 13 to pipe 16, and consequently oil under pressure is admitted to piston 19 of the damper regulator unit D^1 . The piston 19 is then shifted downwardly, and the sheave is 75 also pulled down by the chain 21, so that the rods 23 and 24 operate to partially close the stack damper 5 and the ash pit doors 26.

Fuel oil is also supplied from pipe 16 to pipe 42 and acts on the top of the piston 29 80 of the regulator unit V^1 to close the valve 28 and thereby cut off the direct flow of fuel oil at full pressure to the oil burners.

As the piston 19 moves downwardly, the piston valve 46 also moves and cuts off communication between pipes 16 and 42, but at the same time, communication is opened from supply pipe 2 through annular port 47 to pipe 42, so that the oil pressure on piston 29 of the regulator unit V^1 is maintained, to hold the valve 28 closed. 85

The valve 28 of the regulator unit V^2 is still open, since it is controlled by the damper regulator unit D^2 , so that this valve permits the flow of fuel oil under pressure 90 from pipe 2 through pipe 48 to the reducing valve R^1 and being set for 200 pounds, permits the flow of fuel oil to pipe 44 at a pressure of 200 pounds, so that the pressure of oil supplied to the burners B is now 200 95 pounds instead of 225 pounds and an intermediate fire is maintained. 100

Should the steam pressure increase to a still higher predetermined degree, the master controller unit M^2 will operate, as described in 105 connection with the unit M^1 , to effect the movement of the damper regulator unit D^2 , so as to further close the dampers and also admit fuel oil under pressure to pipe 43. The piston 29 then closes the valve 28 of the regulator unit V^2 , so that the supply of oil is 110 cut off from the reducing valve R^1 and this reducing valve ceases to supply fuel oil to the burners.

The reducing valve R^2 , which is set for 115 175 pounds will now be effective to supply fuel oil to the burners at the reduced pressure of 175 pounds to provide a minimum fire.

A drop in steam pressure causes the reverse action of the pressure regulating mechanism, so that the intermediate pressure is first cut in and upon a further drop in steam pressure, the high pressure flow is 120 opened.

Having now described my invention, what I claim as new and desire to secure by Letters Patent, is:—

1. In a liquid fuel burning apparatus, the combination with a liquid fuel burner, of a 130

liquid fuel supply main, a pump for supplying liquid fuel under pressure to said main, and a plurality of valve mechanisms operative to supply liquid fuel from said main to the burner at a plurality of different pressures, each less than the pressure of liquid fuel in the supply main.

2. In a liquid fuel burning apparatus, the combination with a liquid fuel burner, of a liquid fuel supply main, a pump for supplying liquid fuel under pressure to said main, a device operative to supply liquid fuel from said main to the burner at a pressure less than the pressure in the supply main, another device operative to supply liquid fuel from the main to the burner at another pressure less than the pressure in the main, and means for selectively operating said devices.

20 3. The combination with a steam boiler and a liquid fuel burner for heating the boiler, a liquid fuel supply main, and a pump for supplying liquid fuel under pressure to said main, of a plurality of valve mechanisms for supplying liquid fuel from the supply main to the burner at different pressures less than the pressure of liquid fuel in the supply main and a master controller operated according to the pressure of steam in the boiler for controlling the operation of said valve mechanisms.

4. In a liquid fuel burning apparatus, the combination with a liquid fuel burner, of a source of liquid fuel under pressure, a regulating valve for controlling the supply of liquid fuel directly from said source to the burner, a reducing valve for limiting the pressure of liquid fuel supplied to the burner, and a regulating valve for controlling the supply of liquid fuel to said reducing valve.

5. In a liquid fuel burning apparatus, the combination with a liquid fuel burner, of a source of liquid fuel under pressure, a regulating valve for controlling the supply of liquid fuel directly from said source to the burner, a reducing valve for limiting the pressure of liquid fuel supplied to the burner, a regulating valve for controlling the supply of liquid fuel to said reducing valve, and a second reducing valve for supplying

liquid fuel from said source to the burner at a different predetermined pressure.

6. In a liquid fuel burning apparatus, the combination with a liquid fuel burner, of a source of liquid fuel under pressure, a regulating valve for controlling the supply of liquid fuel directly from said source to the burner, a reducing valve for limiting the pressure of liquid fuel supplied to the burner, a regulating valve for controlling the supply of liquid fuel to said reducing valve, a second reducing valve for supplying liquid fuel from said source to the burner at a different predetermined pressure, and a master controller governed by steam pressure for controlling said regulating valves.

7. In a liquid fuel burning apparatus, the combination with a steam boiler and a liquid fuel burner for heating said boiler, of a reducing valve for supplying liquid fuel to said burner at a predetermined pressure, a regulating valve for controlling the supply of liquid fuel from said source to the reducing valve, a second reducing valve for supplying liquid fuel from said source to the burner at a different predetermined pressure, a regulating valve for supplying liquid fuel to the burner directly from said source, and a master controller governed by the steam boiler pressure for controlling said regulating valves.

8. In a liquid fuel burning apparatus, the combination with a steam boiler and a liquid fuel burner for heating the boiler, of a source of liquid fuel under pressure, a regulating valve for controlling the supply of liquid fuel at one predetermined pressure from said source to the burner, a reducing valve for supplying liquid fuel at a different pressure to the burner, a regulating valve for controlling the supply of liquid fuel to said reducing valve, a second reducing valve for supplying liquid fuel to said burner at still another predetermined pressure, and a master controller governed by the steam pressure in the boiler for controlling the operation of said regulating valves.

In testimony whereof I have hereunto set my hand.

SHIRLEY S. WEEKS.
